CLAIM

(22) Filed: **Jul. 24, 2020**

The ornamental design for an oral care implement, as shown and described.

Related U.S. Application Data

DESCRIPTION

(62) Division of application No. 29/684,593, filed on Mar. 22, 2019, now Pat. No. Des. 895,973.

FIG. 1 is a front perspective view of an oral care implement according to a first embodiment of the new design;

(51) **LOC (13) Cl.** **04-02**

FIG. 2 is a rear perspective view thereof;

(52) **U.S. Cl.**

FIG. 3 is a front view thereof;

USPC **D4/101**

FIG. 4 is a rear view thereof

(58) **Field of Classification Search**

FIG. 5 is a left side view thereof;

USPC D4/100-138, 199; D24/176, 181

FIG. 6 is a right side view thereof;

CPC A46B 2200/1066; A46B 2200/1073; A46B

FIG. 7 is an enlarged top view thereof;

2200/1086; A46B 5/0095; A46B 9/04;

FIG. 8 is an enlarged bottom view thereof;

A46B 13/023; A61C 17/16; A61C 17/222

FIG. 9 is a front perspective view of an oral care implement according to a second embodiment of the new design;

See application file for complete search history.

FIG. 10 is a rear perspective view thereof;

(56) **References Cited**

FIG. 11 is a front view thereof;
